UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

DESIGN FOR A SLICING-MACHINE CASING

Application filed December 16, 1929. Serial No. 33,793. Term of patent 14 years.

To all whom it may concern:

Be it known that I, WILLIAM J. CAMPBELL, a citizen of the United States, residing at Indianapolis, in the county of Marion and State of Indiana, have invented a new, original, and ornamental Design for a Slicing-Machine Casing, of which the following is a specification, reference being had to the accompanying drawings, forming part thereof.

The figures are illustrations of my slicing machine casing, showing my new design.

Figure 1 is a rear view; Figure 2 is a front elevation; and Figure 3 is an end elevation.

I claim:

The ornamental design for a slicing machine casing, as shown.

WILLIAM J. CAMPBELL.
